RAILWAY CAR RETARDER

Walter F. Mitchell, Birmingham, Ala., assignor
to United States Steel Company, a corporation
of New Jersey

Application September 18, 1951, Serial No. 247,179

7 Claims. (Cl. 188—62)

1

The present invention relates to apparatus for controlling the speed of rolling railway equipment.

It is an object of this invention to provide apparatus adapted to be installed in a trackway for retarding the speed of moving railway equipment or cars on down grade tracks so as to prevent acceleration to undesirable speeds while the cars are approaching a bumper block, a cushioned car stop or the like.

An example of one form which the invention may take is described in the following specification and shown in the accompanying drawings in which:

Figure 1 is a plan view;

Figure 2 is a side elevational view partly in section taken on the line II—II of Figure 1;

Figure 3 is an enlarged detailed view taken on the line III—III of Figure 1;

Figure 4 is an end view partly in section taken on the line IV—IV of Figure 2; and

Figure 5 shows an enlarged detail view of the linkage system.

Referring more particularly to the drawings, reference numeral 2 indicates a pit located under a portion of a down grade tram trackway 4. A fabricated base frame 6 is rigidly set in the pit 2, and supports the rails 8 of the trackway 4 above it. Concrete may be poured around the outside of the frame 6 to anchor it firmly within the pit. A secondary frame 10 is mounted for pivotal movement within the frame 6 below the trackway 4 and intermediate the rails 8. The forward end 12 of the secondary frame 10 is suspended by means of a pair of depending spaced eye bolts 14 which are connected, by means of nuts 18, to a transverse supporting beam 16 which is positioned across one end of the base frame 6. The secondary frame is connected for pivotal movement on the end of the eye bolt by means of pins 20, each of which is carried in a bronze bushing 22 in the lower end of each eye bolt.

The rear end 24 of the secondary frame is pivotally connected with and supported by a pair of spaced angularly shaped links 26 by means of pins 28 which pass through bronze bushings 30 carried by each of the links, as best shown in Figure 5. Blocks 34 are welded to the frame 10 and are positioned against the flat sides of the heads of the pivot pins 20 and 28 to prevent the rotation of the pins relative to the frame 10. This assures that the pins will rotate only in the bushings. The other ends of the links 26 are connected with a pair of spaced lever arms 32 which are keyed onto a rotatable transverse shaft 36. The ends

2

of the shaft 36 are journaled in bearings 38 mounted on the two sides of the base frame 6. Links 26 are so shaped that rotation of the shaft 36 in the counterclockwise direction, as shown in Figure 2, causes the links to lower the rear end 24 of the frame 10. Rotation of the shaft 36 is effected by means of a lever arm 42 which is keyed onto the shaft 36 intermediate the lever arms 32. Lever 42 is connected with the end of a piston rod 44 which projects from a pivotally mounted, doubled-acting fluid cylinder 46. The cylinder 46 is mounted in a bracket 48 which is supported at one end by a transverse beam 50 secured to frame 6 and at its other end by a short structural angle 53 which projects inwardly from the end of the frame 6. When pressure fluid is applied to cylinder 46 through fluid supply line 55, the piston rod 44 is ejected therefrom, which action rotates the shaft 36 in a counterclockwise direction to move the links 26 so that the rear end of the frame 10 is lowered. Conversely, pressure fluid is supplied to the head end of the cylinder 46 to retract the piston rod within the cylinder and rotate the shaft 36 in the clockwise direction when it is desired to raise the frame 10. Bumpers 52 and 54 are provided adjacent the forward and rearward end of the frame 10 respectively so as to limit the horizontal movement of the frame and to absorb any end thrust imparted thereto. The bumpers 52 and 54 are rigidly mounted on the base frame 6.

The lever which supports the upper end of the links 26 comprises hubs 56 which are keyed onto the shaft 36 adjacent each end thereof. Each hub is provided with two spaced apart projecting arms 58 which have aligned holes 60 in the ends thereof. A pin 62 which is carried by the projections on each of the hubs 56 supports a bushing 64 between the projections. Each of the bushings 64 is formed for slip fit in a bearing seat 66 in the ends of links 26. The design of the supporting linkages for the rearward end 24 of the secondary frame 10 is such that the frame is locked into position when it is raised. This is accomplished by having the line of action through the pivot points A and B and the body of link 26 on opposite sides of the center line of the shaft 36 as shown in Figure 5. As the load on the frame 10 is increased, the torque acting through the levers 32 is also increased. This torque acts to pull the link 26 towards the center line of the shaft 36, thus locking it and the frame 10 into position.

A pair of spaced bearing 68 is mounted on the upper surface of the frame 10 intermediate its

ends to rotatably support a wheel shaft 70 having a pair of rubber-tired wheels 72 keyed thereto. As shown in Figure 1 the wheels are mounted on the ends of the shaft which projects from each of the two bearings. A brake drum 74 is keyed onto the shaft 70 around its center portion intermediate the bearings 68. As best seen in Figure 3, a brake band 76 is disposed around the brake drum 74 in the conventional manner with one end of the brake band being connected to one end of an adjusting nut 78 while its other end is secured to a bracket support 80 which is mounted on the supporting frame 10 adjacent to the brake drum 74. A link member 82 is pivotally connected at one end to the bracket support 80 adjacent the point to which the end of the brake band is anchored. The opposite end of the link 82 is pivotally connected with a piston rod 84 which projects from a fluid cylinder 86 pivotally mounted on the supporting frame 10 adjacent the bracket support 80. A fluid supply line 87 is provided for furnishing pressure fluid to the cylinder 86. The link 82 is provided with an opening 88 for accommodating a bolt 90 which is pivotally connected with the bracket support 80 and projects upwardly therefrom through the link 82. The projecting portion of the bolt 90 is threaded to accommodate lock nuts 92 thereon. A compression spring 94 is circumferentially mounted on the projecting portion of the bolt 90 with one end bearing on the link 82 and its other end bearing against a washer 96 which is fitted around the bolt 90 adjacent to the lock nut 92.

The tension of the brake band 76 around the brake drum 74 is adjusted by means of the adjusting nut 78 so that the rotation of the wheel shaft 70 is constantly under restraint. When it is desired to release the brake band from the drum 74 in order to allow the wheel shaft to rotate freely, pressure is applied in the fluid cylinder 86 to eject the piston rod 84 which in turn raises the link member 82 to compress the spring 94. The raising action of the link 82 elevates the adjusting nut 78 a sufficient distance to free the brake band from the brake drum. When it is desired to reapply the restraining action, pressure is released from the cylinder 86 and the link 82 is lowered to normal position by the compressing action of the spring 94.

In operation, when it is desired to retard the speed of railway tram cars travelling over the trackway 4 the secondary platform 10 is raised into operating position, as shown in solid lines in Figure 2, by actuating cylinder 46 to retract the piston rod 44 and rotate shaft 36 in the clockwise direction by the lever 42. Rotation of the shaft causes the links 26 to raise the end 24 of the frame 10. When frame 10 is raised into operating position a circumferential portion of each of the wheels 72 projects above the rails 8 a sufficient distance to contact the smooth bottom of a tram car travelling over the trackway 4. As each car passes over the car retarder its bottom contacts the wheels 72 which then bear part of the weight of the car. The moving car turns the wheels 72 and shaft 70 against the restraint created by the brake mechanism. Thus, part of the kinetic energy of the moving car is absorbed and the speed of the car is reduced. In the case of a coupled trip or train of cars, each car will be retarded a given amount as it in turn passes over the retarder until the movement of the train is reduced to a desirable speed or brought to a stop, as the case may be. If the train is

stopped and it is then desired to let it move further down the grade, the set brake can be released by means of applying pressure to the fluid cylinder 86. When it is desired to permit rolling equipment to pass over the car retarder without engaging the wheels 72 the shaft 36 is rotated in the counterclockwise direction to rotate the links 26 and lower the end 24 of the platform 10 to the position shown in broken lines in Figure 2.

While one embodiment of my invention has been shown and described it will be apparent that other adaptations and modifications may be made without departing from the scope of the following claims.

I claim:

1. Apparatus for retarding the movement of a vehicle traveling on a railway trackway which comprises a trackway, rails on said trackway, at least one wheel rotatably mounted below said trackway intermediate the rails thereof with its axis disposed transversely of said trackway, the rim of said wheel being covered with a friction-inducing material, a circumferential portion of said wheel projecting above said trackway to contact the bottom of a vehicle traveling thereon, and means for restraining the rotation of said wheel.

2. Apparatus for retarding the movement of a vehicle traveling on a railway trackway which comprises a trackway, rails on said trackway, a shaft rotatably mounted transversely beneath said trackway intermediate the rails thereof, at least one wheel secured on said shaft, the rim of said wheel being covered with a friction-inducing material, a circumferential portion of said wheel projecting above said trackway to contact the bottom of a vehicle traveling thereon, and brake means for restraining the rotation of said shaft.

3. Apparatus for retarding the movement of a vehicle traveling on a railway trackway which comprises a trackway, rails on said trackway, a main supporting frame rigidly disposed beneath said trackway intermediate the rails thereof, a secondary frame mounted for pivotal movement within said main frame, a shaft rotatably journaled on said secondary frame transversely of said trackway, at least one wheel having a rim of friction-inducing material secured on said shaft, a circumferential portion of said wheel projecting above the rails of said trackway when said secondary platform is in operating position, brake means operatively connected with said shaft for restraining the rotation thereof, and means carried by said main frame for raising and lowering said secondary frame to thereby raise and lower said circumferential portion above and below the rails of said trackway.

4. Apparatus for retarding the movement of a vehicle traveling on a railway trackway which comprises a trackway, rails on said trackway, a main supporting frame rigidly disposed beneath said trackway intermediate the rails thereof, a secondary frame disposed within said main frame, said secondary frame being pivotally connected at one end to said main frame, a rotatable transverse shaft carried by said main frame above the end of said secondary frame remote from said pivoted end, a pair of spaced lever arms keyed to said shaft, a pair of angularly shaped links each attached at one end to one of said lever arms and depending therefrom to a pivotal connection with the end of said secondary frame remote from said pivoted end whereby said secondary frame is raised and lowered upon rotation of said shaft, means for rotating said shaft,

a wheel shaft rotatably journaled on said secondary frame intermediate said pivoted end and said link-supported end transversely of said trackway, at least one wheel having a rim of friction-inducing material secured on said wheel shaft, a circumferential portion of said wheel projecting above the rails of said trackway when said secondary frame is in operating position, and brake means operatively connected with said wheel shaft for restraining the rotation thereof.

5. Apparatus for retarding the movement of a vehicle traveling on a railway trackway as defined in claim 4 characterized by said means for rotating said shaft including a lever arm keyed onto said shaft, a fluid cylinder having a piston rod slidably fitted therein pivotally mounted on said main frame adjacent said shaft, the outer end of said piston rod being pivotally connected with said last named lever arm, and fluid-supply lines for said fluid cylinder.

6. Apparatus for retarding the movement of a vehicle traveling on a railway trackway as defined in claim 5 characterized by bumper bars mounted transversely in said main frame adjacent the ends of said secondary frame for limiting the longitudinal movement thereof.

7. Apparatus for retarding the movement of a

vehicle traveling on a railway trackway as defined in claim 4 characterized by said brake means including a brake drum secured onto said wheel shaft, a brake band adjustably fitted around said brake drum, adjustable spring means connected with said brake band for maintaining the same in restraining engagement with said brake drum, and fluid operated means connected with said brake band and said spring means for releasing said brake band from restraining engagement with said brake drum to thereby permit said wheel shaft to rotate freely.
